BAG FILLING MACHINE

Arno Andreas, Munster, Germany, assignor to
 Bagpak, Inc., New York, N. Y., a corporation
 of Delaware

Application March 16, 1932, Serial No. 599,151
 In Germany March 30, 1931

13 Claims. (Cl. 249—60)

This invention relates to machines for filling bags with divided material such as cement, and more particularly to an improved machine of the type in which the bag and contents are weighed coincidentally with the filling operation.

An object of the invention resides in the provision of improved means for supporting a bag in filling position, including interconnections with the weighing mechanism. More specifically, the invention involves a bag support having a spout adapted to enter a valve opening in the bag for guiding material thereinto, and means including a balance arm to weigh the bag on said support, all constructed so that during the filling and weighing operation the movement of the spout with respect to a conduit for feeding material thereinto is practically negligible. Another object is to provide such means in which the weight carrying portion of the balance arm travels sufficiently to operatively control a cut-off valve for the feed of material. Still another object is to construct a device of the character mentioned in which the bag support is carried with the other parts of the device so that the need for guides for the support is obviated. A feature of the invention resides in such a construction which is simple and inexpensive to manufacture, efficient in operation, durable in service and particularly compact and light in weight. Other objects and advantages will be in part apparent and in part pointed out in connection with the following detailed description of embodiments of the invention.

In the accompanying drawings:

Fig. 1 is a diagrammatic side elevation, partly in section, of one form of bag filling machine in accordance with the invention.

Fig. 2 is a view similar to Fig. 1 of another form of the invention.

Figure 3 is a view in horizontal section on line 3—3 of Figure 1.

Referring first to Fig. 1 there is shown at 1 a frame supporting a propelling device 2 to which the material to be filled into bags or other containers is fed through a supply hopper 3. This hopper is shown provided with an outlet conduit 4 aligned with a spout 5 adapted to enter the valve opening in a valve bag. This spout 5 is shown carried with a rack 6 having a platform 7 for supporting the bottom of the bag. The rack may rest through a pair of arms 8, as illustrated in Figure 3, on knife edges 9a carried on triangular or V-shaped lever arm 9.

The forward ends of the lever 9 may be supported through knife edges 9a in suitable grooves 10a of forwardly extending arms 10 carried rigidly with the frame 1. The rear end of the V-shaped lever 9 is shown supported through link 11 on the forward portion of balance arm 12 of the weighing mechanism, the link 11 being pivotally connected to the lever 9 and balance arm 12 by means of knife edges 9b and 12a, respectively. A suitable weight supporting tray 13 is shown hung on the rear portion of the balance arm 12 through knife edge 12b. The rack 6 is shown provided with a rearwardly extending arm 14, the rear end of which is hung from the forward portion of the balance arm through a link 15 having a hook 15a for engaging a hook 14a on the arm 14. The upper end of the link 15 may be hung on the balance arm through a knife edge 12c.

There is shown at 16 a slide or gate valve adapted to close the opening in the outlet conduit to cut-off the flow of material from the hopper. This valve may be connected through a suitable lever 18 pivoted as at 17 and adapted to cooperate with an electromagnet 19. The balance arm 12, at the beginning of the filling operation, may rest upon a suitable support 20 carried by the frame 1, and have an extension 21 for contacting, when the bag is full, with a plate 22 connected through wires 24 and 25 to electromagnet 19, battery 23 and frame 1, for completing the circuit and causing the magnet to be energized to close the valve 16.

The operation of the machine will no doubt be apparent from the above description of its construction but may be summarized as follows. A bag having been placed on the rack 6 with its valve opening over the spout 5 and the valve 16 having been opened, manually or through any convenient device (not shown), the propeller 2, 40 which preferably rotates constantly, feeds material from the hopper 3 into the bag. As the bag fills, the bag rack descends, finally overcoming the balancing effect of the weight on the tray 13, with the result that the projection 21 on the balance arm 12 contacts with the plate 22, effecting closing of the valve 16 in the manner indicated.

In the construction illustrated, it will be apparent that the effective moment arm of the bag support is considerably greater than the moment arm of the weight tray, and that in this manner the deflection or downward movement of the bag rack may be made practically negligible. That is to say, as the material for filling the bag runs into the latter, the bag rack will descend, and it 55

is desirable to have the movement of the rack as small as possible in order that the spout 8 will not come out of line with the conduit 4. At the same time, by the inter-position of the lever member 5 between the bag rack 6 and the balance arm 12, the travel of the projection or extension 21 on the balance arm may be made suitable for effecting the contact in order to cause the closing of valve 16. Moreover, not only is the travel of 10 the bag rack slight, but also the weight required to counterbalance the weight of the rack and filled bag is relatively small. By means of the suspension of the bag rack, the two spaced points on the balance arm 12, and on the frame 1, tilting 15 of the bag rack in the plane of Fig. 1 is avoided. At the same time, by providing a plurality of supports 8a, sideways tilting of the rack is eliminated. Moreover, the bag rack is freely suspended.

While a specific lever construction is illustrated, 20 it will be understood that other classes and arrangements of levers may be employed. It will also be understood that the particular three-point suspension of the bag rack, while preferred, may be modified without sacrificing the advantage of 25 the limited travel of the bag rack.

Referring now to Fig. 2, there is shown a construction similar to that shown in Fig. 1 and including a frame 28 supporting a propeller or turbine 29 for feeding material. The material may 30 be delivered to the propeller through a hopper 30 which may advantageously be connected with the propeller housing by an inclined passage 31, constructed and arranged so that the material flows down the side thereof in a uniform manner. This 35 passage 31 may be formed with a bend in the same so that the material is required to reverse its direction before passing into the propeller housing, its rate of travel being thus further slowed up. In the discharge or outlet conduit 32 40 of the propeller housing, there is shown a valve 34, the closing of which may be controlled by an electromagnet 33. When the valve 34 is closed, and the propeller continues to rotate, there is considerable swirling of the material in the propeller housing, with the result that a great deal 45 of dust is thrown about and the material may be objectionably heated. In order to minimize this tendency, there is shown provided in the housing a baffle 35 which provides a passage 35a 50 through which material may be returned by the propeller into the hopper. A baffle 35b may be provided to prevent material from the hopper entering this passage. In this manner, the material is simply re-circulated instead of being 55 ground by the propeller. The valve 34 may be arranged so that when it closes the conduit 32 it simultaneously opens the passage 35a. The valve 34 60 may be constructed as a full feed valve, having an opening 36 therein so that some material continues to flow through the opening even after the valve is closed. In this event, a dribble feed valve 38 is preferably provided in front of the valve 34, and controlled by an electromagnet 37.

As shown, the construction of the spout 39, 65 lever 40, links 41, 42, balance arm 43, and bag rack 44 may be similar to that shown and described in connection with Fig. 1. Instead of a weight tray, a weight 45 is shown slidably carried on the scale beam, which beam is adapted 70 to rest on a projection 46, before the filling operation commences.

Even though the fit between the spout 39 and the conduit 32 is close, and though the movement of the spout with respect to the conduit is very 75 slight, it may still be desirable to surround the

joint with a dust collecting device 47 which may be made of flexible material and of generally annular shape. Chamber 47 in this means may be connected through a tube 48 to any suitable vacuum means (not shown).

Mechanism for automatically and successively closing the valves 34 and 38 may take the following form. The balance arm 43 is shown provided with an extended portion 49 adapted to contact with U-shaped spring 50 which is secured 10 at one end through insulating material 51 to frame 28. The free end of the spring 50 is shown carrying a pin 52 normally contacting with plate 53 which is connected through wire 54 and battery 55 to magnet 33. As the scale beam tilts, when 15 the bag is nearly filled, the extension 49 contacts with the lower arm of the U-shaped member 50, thus completing the circuit 55-33-28-43-49-50-52-53-54, and closing the valve, through co-action with suitably pivoted arm 34a on which 20 the valve is carried. As the material continues to flow into the bag through opening 36 in valve 34, the extension 49 rises till pin 52 is lifted from plate 53 and caused to contact with plate 56 which is connected through wires 58 and 59 to battery 57 25 and electromagnet 37. The flow of current is then 57-59-37-28-43-49-50-52-53-58. Excitation of this magnet effects closing of valve 38, thus entirely cutting off the flow of material into the bag. The closing of the valves is thus substantially instantaneous, with resultant accuracy in weights. The scale beam extension 49 descends, when the full bag is removed from the scale, and thus effects deenergization of the magnets. Any suitable means, not shown, may be 35 employed for opening valves 34 and 38.

As already indicated the lever construction for supporting the bag is such that the counterbalancing weight on the scale mechanism need be but a small fraction of the weight of the bag support 40 and a full bag. The present construction is thus especially suited to employment in portable devices. Accordingly, the frame 28 is shown provided with rollers 60 and with jacks 61 for lifting the machine off the rollers while the machine is 45 operating. Each jack is shown threaded for engagement with flanges 62 on frame 28. By adjusting the jacks the machine may be leveled.

The terms and expressions which I have employed are used as terms of description and not of 50 limitation and I have no intention, in the use of such terms and descriptions, of excluding any equivalents of the features shown and described, or portions thereof, but recognize that various 55 modifications are possible within the scope of the invention claimed.

I claim:

1. In a machine for filling containers with divided material comprising a hopper, a propeller housing, a constantly rotating propeller therein 60 for feeding material, and valve bag supporting means including a spout adapted to enter the bag and through which material enters the bag, weighing mechanism including a balance arm, a valve for cutting off the flow of material into the 65 spout, means to close said valve controlled by the weighing mechanism, and means to continuously interconnect said bag supporting means with the balance arm during the filling operation, said interconnecting means including a lever arm inter- 70 posed between said bag supporting means and said balance arm and constructed and arranged so that the effective moment arm of the said bag supporting means is greater than the effective moment arm of the balance.

2. In a machine for filling containers with divided material comprising a hopper, a propeller housing, a constantly rotating propeller therein for feeding material, and means including a spout to support the container in filling position, said propeller advancing material through said spout into the container, weighing mechanism including a balance arm, valve means for cutting off the flow of material into the container, means to close the valve means controlled by the weighing mechanism, and means to continuously interconnect said bag supporting means with the balance arm during the filling operation, said interconnecting means including a lever arm interposed between said bag supporting means and said balance arm and constructed and arranged so that the effective moment arm of the said bag supporting means is greater than the effective moment arm of the balance. 5
- 5 10 15 20 25 30 35 40 45 50 55 60 65 70 75
3. In a machine for filling containers with divided material comprising a hopper, a propeller housing, a constantly rotating propeller therein for feeding material, a frame, rollers adapted to portably support the frame, means to support the container in filling position on the frame including a spout, said propeller serving to convey material through said spout into the container, weighing mechanism including a balance arm, valve means for cutting off the flow of material into the container, means to close the valve means controlled by the weighing mechanism, and means to continuously interconnect said bag supporting means with the balance arm during the filling operation, said interconnecting means including a lever arm interposed between said bag-supporting means and said balance arm and constructed and arranged so that the effective moment arm of the said bag supporting means is greater than the effective moment arm of the balance. 20
- 30 35 40 45 50 55 60 65 70 75
4. In a machine for filling containers with divided material comprising a hopper, a propeller housing, a constantly rotating propeller therein for feeding material, valve bag supporting means including a spout adapted to enter the bag and to convey material to said bag, weighing mechanism including a balance arm, a valve for cutting off the flow of material into the spout, means to close said valve controlled by the weighing mechanism, and means interposed between the bag supporting means and the balance arm for suspending the bag supporting means at a plurality of points separate from the balance arm and operatively interconnecting the bag supporting means with the balance arm throughout the filling operation. 25
- 45 50 55 60 65 70 75
5. In a machine for filling containers with divided material comprising a hopper, a propeller housing, a constantly rotating propeller therein for feeding material, means to support the container in filling position including a spout to convey material from said propeller housing into the container, weighing mechanism including a balance arm, valve means for cutting off the flow of material into the container, means to close the valve means controlled by the weighing mechanism, and means interposed between the bag supporting means and the balance arm for suspending the bag supporting means at a plurality of points separate from the balance arm and operatively interconnecting the bag supporting means with the balance arm throughout the filling operation. 30
- 55 60 65 70 75
6. In a machine for filling containers with divided material, means to support the container in filling position, means to convey material into the container, weighing mechanism including a balance arm, valve means for cutting off the flow of material into the container means to close the valve means controlled by the weighing mechanism, and means interposed between the bag supporting means and the balance arm for suspending the bag supporting means at a plurality of points separate from the balance arm and operatively interconnecting the bag supporting means with the balance arm throughout the filling operation. 35
- 65 70 75
7. In a machine for filling bags with divided material, a hopper, a propeller housing, a constantly rotating propeller therein for feeding material, a valve at the outlet side of the propeller, and a baffle in the hopper forming a passage for material advancing to the propeller and a passage for returning material from the propeller to the first-named passage, said valve being constructed and arranged to simultaneously restrict the flow of material out of the housing and open the second-named passage. 40
- 45 50 55 60 65 70 75
8. In a machine for filling bags with divided material, a hopper, a propeller housing, a constantly rotating propeller therein for feeding material, a valve at the outlet side of the propeller, and a baffle in the hopper forming a passage for material advancing to the propeller and a passage for returning material from the propeller to the first-named passage, said valve being constructed and arranged to simultaneously restrict the flow of material out of the housing and open the second-named passage, and being adapted to permit a relatively small flow of material therewith. 45
- 45 50 55 60 65 70 75
9. In a machine for filling bags with divided material, a hopper, a propeller housing, a constantly rotating propeller therein for feeding material, a valve at the outlet side of the propeller, and a baffle in the hopper forming a passage for material advancing to the propeller and a passage for returning material from the propeller to the first-named passage. 50
- 50 55 60 65 70 75
10. In a machine for filling containers with divided material comprising a hopper, a propeller housing, a constantly rotating propeller therein for feeding material, and a spout communicating with said propeller housing and serving to support the container in filling condition and to convey material into the container, weighing mechanism including a balance arm, valve means for cutting off the flow of material into the container, and a lever arm operatively interposed between the supporting means and the balance arm for continuously connecting said supporting means and balance arm throughout the filling operation. 55
- 55 60 65 70 75
11. In a machine for filling containers with divided material comprising a hopper, a propeller housing, a constantly rotating propeller therein for feeding material, and a spout communicating with said propeller housing and serving to support the container in filling condition and to convey material into the container, weighing mechanism including a balance arm, valve means for cutting off the flow of material into the container, and a V-shaped lever arm extending at either side of the supporting means and operatively interposed between the same and the balance arm. 60
- 60 65 70 75
12. In a machine for filling bags with divided material, a hopper, a propeller housing, a constantly rotating propeller therein for feeding material, a valve at the outlet side of the propeller, a baffle in the hopper forming a passage for material advancing to the propeller and a passage for returning material from the propeller to the first-named passage, said valve having sufficient length and being so mounted that it 70
- 70 75

simultaneously restricts the flow of material out of the housing and opens the second-named passage, and having an opening therein to permit a relatively small flow of material therewith, and a second valve to close said opening.

5 13. In a machine for filling bags with divided material, a hopper, a propeller housing, a constantly rotating propeller therein for feeding material, a valve at the outlet side of the propeller, a baffle in the hopper forming a passage for material advancing to the propeller and a pas-

sage for returning material from the propeller to the first-named passage, said valve having sufficient length and being so mounted that it simultaneously restricts the flow of material out of the housing and opens the second-named passage, 5 and having an opening therein to permit a relatively small flow of material therewith, a second valve to close said opening, and weighing mechanism supporting a bag in filling position and controlling said valves.

10

ARNO ANDREAS.
